AUTOMATIC HAMMER SAFETY FOR
AUTOMATIC GUNS

Alonzo F. Gaidos, Redwood City, Calif.

Application July 3, 1946, Serial No. 681,281

1 Claim. (Cl. 89—140)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to an improved fire control mechanism for firearms of the semi-automatic type.

There are many firearms of the semi-automatic type which have been converted to provide full automatic fire. However, such conversion usually necessitates alteration of existing major parts of the firearm as well as providing new additional parts. Further, known conversions are not entirely safe inasmuch as the hammer is not positively blocked in automatic fire during the intervals that the breech is unlocked. Thus it is possible for such hammer to prematurely fire the weapon before the bolt is fully locked due to failure to close.

Accordingly, it is an object of this invention to provide a simple fire control mechanism to convert a semi-automatic firearm to selectively obtain full automatic fire without the necessity of performing major machining operations on existing components.

Another object of this invention is to provide a fire control mechanism for a firearm that positively blocks the hammer until the bolt is fully locked for each round fired, thereby substantially eliminating any danger of premature discharge of the firearm.

A particular object of this invention is to provide a fire control mechanism for a firearm commonly known as the U. S. Carbine, Cal. .30, M1, which as issued, affords only means to fire the weapon semi-automatically.

Another object of this invention is to provide a fire control mechanism for a firearm which is controlled by the position of the operating slide of such firearm.

The specific nature of the invention as well as other objects and advantages thereof will clearly appear from a description of a preferred embodiment as shown in the accompanying drawings in which:

Fig. 1 is a side elevational view of a firearm shown with the stock removed which embodies the preferred form of this invention. In such figure the inertia member is shown in the retracted position and the hammer latch is engaged by the hammer.

Fig. 2 is a fragmentary detail view showing the forward end of the actuating bar engaging the front end of the inertia member of the firearm.

Fig. 3 is a fragmentary detail top elevational

view of the trigger guard shown with the hammer removed to illustrate the selector mechanism.

Fig. 4 is a fragmentary detail cross-sectional view taken along the line 4—4 of Fig. 1.

5 Fig. 5 is a fragmentary detail view shown partly in longitudinal section to illustrate the conventional sear mechanism of the firearm.

Fig. 6 is a detail fragmentary view of Fig. 1 showing the hammer latch released from engagement with the hammer by the actuating bar.

Fig. 7 is a side elevational view of the firearm illustrating a modification of the embodiment shown in Fig. 1.

10 Fig. 8 is a perspective view of the hammer latch.

Fig. 9 is a cross sectional view taken along the line 9—9 of Fig. 3.

Fig. 10 is a detail perspective view of the hammer latch stud of Fig. 7.

15 Fig. 11 is a sectional view taken along the line 11—11 of Fig. 1.

Fig. 12 is a fragmentary detail view showing the hammer latch holding the hammer in the cocked position and the actuating bar in the rear-most position.

20 Fig. 13 illustrates a third modification of this invention and is shown in side elevation mounted on the firearm with the hammer in the released position.

Fig. 14 is a top elevational view of the actuating bar shown in Fig. 13.

Fig. 15 is a fragmentary view of Fig. 13 showing the hammer in the cocked position and with the actuating bar in engagement therewith.

25 Fig. 16 is a side elevational view of the firearm embodying a fourth modification of this invention, the hammer being in the released position.

Fig. 17 is a top elevational view of the actuating bar illustrated in Fig. 16.

30 Fig. 18 is a view similar to Fig. 16 showing the hammer in the cocked position and the latch in engagement with such hammer.

Fig. 19 is a perspective view of the selector.

35 While not limited thereto, the invention is particularly applied to semi-automatic firearms of the type having a reciprocating operating slide which functions the bolt between its locked, battery position, and an unlocked, recoiled position.

The invention to be described in more detail 40 later essentially comprises an actuating bar mounted along one side of the firearm adjacent the receiver, one end of such bar being connected to the operating slide while the other end is connected to a hammer latch. The hammer latch 45 is pivotally mounted on the trigger guard of such

firearm. A cam is provided at the rear end of the actuating bar wherein an arm of the hammer latch is secured, such cam being provided to actuate the latch. A selector is provided to shift the position of the sear to selectively produce either semi-automatic or full automatic fire, as will be explained in more detail later. The hammer latch is utilized in automatic fire to block the hammer until such time as the bolt has been positioned in its locked position by the operating slide before release of such latch is effected by the actuating bar to prevent premature ignition of a cartridge.

In Fig. 1 there is shown in assembled relation a firearm of the semi-automatic type embodying this invention. The major elements of such firearm are substantially identical to the U. S. Carbine, Cal. .30, M1 which, as is commonly known, is constructed to fire semi-automatically. Such firearm comprises mainly a receiver 1, a barrel 2, a bolt 3 and a trigger guard 4. Barrel 2 is threadably secured to receiver 1 in a conventional manner and trigger guard 4 is mounted on the underside of receiver 1. Oppositely disposed ribs 5 (Fig. 4) provided on the rear end of receiver 1 engage corresponding ways 6 in trigger guard 4. The forward end of such trigger guard is secured to the receiver by a transverse headed pin 7.

Bolt 3 is horizontally mounted within receiver 1 and reciprocates therein on suitable horizontal ways provided on the interior of such receiver. On the underside of barrel 2 there is slidably mounted an operating slide 11 and such slide is connected to bolt 3 by the rearwardly projecting offset handle portion 11a of such slide. The elements thus far described are all conventional.

In the preferred modification of this invention, an actuating bar 14 is provided which is slidably mounted on the left side of receiver 1 as shown in Figs. 1 and 2. The forward end of bar 14 terminates in a hook 15 which is bent inwardly and engages the forward end of operating slide 11. The rear end 16 of bar 14 is of substantially greater width. A forwardly opening slot 17 is provided on the front end of enlarged portion 16 which is engaged by headed pin 7. The wood of the stock (not shown), prevents removal of the pin. A cam slot 18 is cut in portion 16. The forward end 20 of cam slot 18 is enlarged to permit assembly of actuating bar 14 to a hammer latch 19.

A conventional trigger 21 and sear 22 as shown in Fig. 5 are pivotally mounted in trigger guard 4 on a novel selector 23. A sear spring 37 is mounted between sear 22 and trigger 21 urging sear 22 forwardly. Selector 23 comprises a shaft portion 24 and a knob portion 25, such knob portion being preferably formed integrally with shaft 24 and located exteriorly of the trigger guard to permit convenient manual rotation thereof. Shaft 24 is of enlarged diameter immediately adjacent a hub 12 provided on the inside face of knob 25 as shown at 26. A central portion 27 of shaft 24 is eccentrically formed with respect to the axis of shaft 24. The eccentric portion 27 passes through a slot-like hole 28 in sear 22. Two oppositely disposed notches 29 are provided on hub 12 each of which is selectively engaged by a detent 31 to be later described. Rotation of selector 23 between two 180° displaced positions indicated by notches 29 moves sear 22 longitudinally to selectively permit normal semi-automatic fire of the firearm or full automatic fire as will be later described.

Hammer latch 19 is a lever-like member (Fig. 8) pivotally mounted at the rear end thereof on

large diameter portion 26 of selector 23. A fixed headed stud 32 projects transversely from the forward end of latch 19. Such stud engages the cam slot 18 when actuating bar 14 is assembled to the gun by inserting the headed portion of stud 32 through the enlarged hole 20 in cam slot 18 and then sliding bar 14 forwardly to engage pin 7 in slot 17 and hook end 15 with slide 11. An inwardly projecting lug or ear 33 is provided approximately in the center of latch 19 and is shaped to engage the hammer 34 of the firearm and prevent hammer 34 from rotating forwardly to fire the gun except when the bolt is in battery position, as will be presently described. Detent 31 is formed by bending one end of a torsion spring 35. Such spring is mounted on a pin 36 which is also utilized to pivotally mount hammer 34. The other end of torsion spring 35 is hooked about trigger guard 4 as shown in Fig. 3.

For semi-automatic fire, selector 23 is turned as shown in Fig. 6. In such position detent 31 engages one of the notches 29 thereby yieldingly securing selector 23 in the selected position. Eccentric portion 27 on such selector 23 is then in a forward position, and as such eccentric lies within slot-like hole 28 of sear 22, the sear is biased forwardly by sear spring 37. When hammer 34 is rotated rearwardly about pin 36 by recoil movement of the bolt 3, the forward end of sear 22 engages a sear notch 38 provided on the lower rear end of hammer 34. Sear 22 is forced rearwardly by the greater bias of hammer spring 40 and the rear end thereof then comes to rest on top of an upstanding projection 39 provided on trigger 21.

When such trigger is pulled rearwardly, the forward end of sear 22 is disengaged from sear notch 38 releasing hammer 34. As the load of hammer spring 40 is removed from sear 22, the bias of sear spring 37 urges sear 22 forwardly so that the rear end of sear 22 drops off projection 39. On the recoil stroke of bolt 3, the forward end of sear 22 again engages sear notch 38 of hammer 34 thereby holding such hammer in the cocked position irrespective of the fact that the trigger remains pulled. Hammer 34 cannot be released until the pressure of the finger is removed from trigger 21, because sear 22 is in the so-called disconnected position. That is, the rear end of sear 22 lies forward of and abutting trigger projection 39 and sear 22 cannot be disengaged from hammer 34 until trigger 21 is permitted to move forwardly sufficiently to permit the bias of hammer 34 to force the rear end of sear 22 rearwardly onto projection 39. Then sear 22 can be released and the gun fired by another pull on trigger 21.

To effect automatic fire, selector 23 is rotated 180° in which position detent 31 then engages the other notch 29 on the selector. Such rotation moves eccentric portion 27 of selector shaft 24 rearwardly, hence limiting the forward movement of sear 22. In this position, when trigger 21 is pulled rearwardly and held there by pressure of the finger, the front end of sear 22 will disengage from sear notch 38. However sear 22 is prevented from moving forward to a cocking position relative to hammer 34 by eccentric 27 and hence sear 22 does not re-engage hammer 34 until trigger 21 is again released. Thus it is apparent that changing the longitudinal position of sear 22 by rotation of selector 23 will provide semi-automatic or full automatic fire respectively. It is desired to point out that full automatic fire can be stopped at will by simply releasing the trigger which brings the front end of sear 22 into the path of

notch 38 of the hammer and permits hammer 34 to force the rear end of sear 22 onto projection 39 thereby holding hammer 34 in the cocked position ready for release by the next pull of the trigger.

In full automatic fire, it is apparent to one skilled in the art that sear 22 is disengaged entirely from hammer 34, and if no other means were provided, the hammer would follow the bolt, firing the gun when the forward movement of the bolt was arrested, independent of whether the bolt is fully rotated into its locked position. Hence it is highly desirable to momentarily delay the fall of hammer 34 until bolt 3 is fully locked, otherwise there would be danger of premature discharge of the cartridge with harmful results, or at any event, a lighter blow would be imparted by the hammer since it would follow the bolt forward.

Hammer latch 19 therefore is arranged to hold hammer 34 in the cocked position until bolt 3 is fully locked before such hammer is released. This action is effective in both automatic and semi-automatic fire. When operating slide 11 drives rearwardly upon discharge of a cartridge from force imparted by a piston (not shown), hammer 34 is rotated to its cocked position by bolt 3. If trigger 21 is not held rearwardly, sear 22 will engage sear notch 38 thereby holding hammer 34 in the cocked position until release of such is effected by pulling trigger 21. On the other hand, if trigger 21 is held rearwardly when bolt 3 recoils, hammer 34 will not be held cocked by sear 22.

However, as slide 11 is forced rearwardly, the rear end of such slide strikes an integral lug 41 provided on the inside of bar 14 just slightly ahead of receiver 1 as shown in Fig. 11. Hence slide 11 forces bar 14 rearwardly. A recess 75 provided on the left side of hammer 34 allows lug 33 of latch 19 to clear hammer 34 as such hammer is rotated rearwardly in a clockwise direction. As bolt 3 approaches the rear end of its recoil travel, cam slot 18 provided in the rear end 16 of actuating bar 14 forces latch 19 downwardly in a counterclockwise direction so that lug 33 of such latch engages hammer 34 slightly below recess 75. Thus hammer 34 is held in a cocked position until the face 11b of operating slide, returning to the battery position, strikes hook 15 on the forward end of bar 14. Actuating bar 14 is then carried forwardly and cam slot 18 raises hammer latch 19 in a clockwise direction so that lug 33 will be raised out of engagement with hammer 34. Hence the bias of hammer spring 40 drives hammer 34 forwardly to strike a firing pin (not shown).

The cocking of the hammer is accomplished near the end of the recoil stroke as explained above and while the hammer 34 is rotating in a clockwise direction, the latch 19 is rotating counterclockwise whereby the lug 33 of latch 19 passes arcuately through recess 75 of hammer 34 and stops a short distance in front of the hammer below recess 75. Therefore when the bolt 2 starts forwardly into the battery position, the hammer also starts forwardly but after the hammer travels a short distance it is stopped and held by the lug 33 of latch 19 until the actuating bar 14 rotates latch 19 clockwise thereby disengaging such hammer.

It is desired to point out that in semi-automatic fire, lug 33 of latch 19 is similarly disengaged from hammer 34 but due to the high speed of the action, such takes place before trigger 21 can be released and pulled again, hence latch

19 is in effect inoperative in semi-automatic fire as far as the operator is concerned.

In Figs. 7 and 12 there is shown in assembled relation a modification of the arrangement above described. In this modification substantially the same components are utilized as those described with the exception of the actuating bar. Selector 23 is again utilized to change sear 22 from automatic to semi-automatic fire positions. A hammer latch 43 (Fig. 10) similar to hammer latch 19 is provided which, however, has a substantially different stud 44 secured to the forward end of such latch, such stud 44 being of greater length and diameter. An annular groove 45 is provided near the outer end of such stud and one end of a torsion spring 46 is mounted on hammer pin 36. Spring 46 extends rearwardly in a horizontal plane and terminates in a detent 47. Such detent engages selector 23 in a manner similar to detent 31 and serves to yieldingly retain selector 23 in one of two positions.

An actuating bar 48 is mounted underneath receiver 1 on the left of such receiver. Bar 48 is a narrow strip-like member and the forward end 49 thereof is of slightly reduced width and is preferably rounded. End 49 of bar 48 is pivotally secured to the rear of operating slide 11 by a transverse pin 50.

Trigger guard 4 is normally cut away as shown at 51 and the cut away portion permits actuating bar 48 to lay snugly against the trigger guard. A substantial portion of the rear end of actuating bar 48 is of reduced width as shown at 52. A sloped cam surface 53 is provided on the extreme rear end of bar 48. The forward end of reduced width portion 52 is sloped upwardly as shown at 54. When the assembled action is placed within the stock of the firearm (not shown) such stock serves to hold actuating bar 48 in its proper place along the side of trigger guard 4.

In this modification, as previously pointed out, actuating bar 48 is connected to the operating slide 11 at all times and therefore moves with such slide. In automatic fire, lug 33 passes through recess 75 on the side of hammer 34 as bolt 3 recoils to rotate hammer 34 to the cocked position. Cam 53 is disengaged from stud 44, hence the bias of spring 46 rotates hammer latch 43 in a counterclockwise direction as shown in Fig. 7. Thus lug 33 of such hammer latch engages hammer 34 to hold it in cocked position. On the counter-recoil stroke, slide 11 returns to its forward position carrying with it actuating bar 48. As slide 11 nears the end of its stroke, after the bolt has been locked, cam 53 strikes stud 44 thereby rotating hammer latch 43 upwardly in a clockwise direction. Thus lug 33 is disengaged from hammer 34, permitting such hammer to go forwardly to strike the firing pin (not shown) thereby effecting discharge of the cartridge only after bolt 3 has been fully locked. Operation of the sear by manipulation of selector 23 to selectively provide semi-automatic and full automatic fire is identical to that above described.

A third modification of a fire control mechanism embodying this invention is shown in assembled relation in Figs. 13 and 15. Such modification essentially comprises an alternate form of actuating bar. The sear and trigger mechanism, including the selector, are identical to that used in the two aforescribed modifications.

In this modification an actuating bar 55 (Fig. 75 14) is provided which is mounted on the right

hand side of trigger guard 4. Such bar is pivotally mounted to the trigger guard at the forward end thereof by transverse pin 7. An offset, vertically upstanding arm 56 of actuating bar 55 rests within a recess 57 provided in slide 11. The rear end 58 of bar 55 is substantially offset so that such rear portion will lie adjacent the right side of hammer 34. An arcuate cam surface 59 is provided on the bottom of the rear portion 58 of bar 55. On the extreme rear end of offset portion 58 a notch 60 is provided for a purpose to be presently described.

A headed stud 61 is secured to the side of hammer 34. Cam surface 59 rides on the top side of stud 61. A torsion spring 62 is provided to bias actuating bar 55 downwardly as will be presently described. One end of such spring rests on top of bar 55 while the other end is secured to the front end of trigger guard 4.

In the fired position as shown in Fig. 13, cam 59 overlies stud 61. Upon rearward movement of the reciprocating bolt 3, hammer 34 is driven rearwardly by the bolt 3 to its cocked position. Cam 59 is held in contact with stud 61 by the bias of torsion spring 62. During automatic fire, trigger 21, of course, is held rearwardly, therefore sear 22 will not engage sear notch 38, hence hammer 34 will tend to follow bolt 3 forwardly, such hammer being urged in the forward direction by the hammer spring. When hammer 34 reaches its cocked position, stud 61 moves off cam surface 59 and into notch 60 of bar 55. Bar 55 is held in this position by spring 62. Thus in effect, actuating bar 55 itself functions as a sear relative to the hammer. On the contour-recoil stroke of slide 11, therefore, hammer 34 will be held in the cocked position by the notch 60 provided at the rear end of bar 55. When, however, slide 11 contacts the upper end of arm 56 provided on the forward end of bar 55, the rear end of bar 55 will be rotated about transverse pin 7 in a clockwise direction. This movement of bar 55 raises notch 60 out of engagement with stud 61 thereby permitting hammer 34 to be driven forwardly, thus effecting discharge of the succeeding cartridge. As in the other modifications, when the sear 22 is in position for semi-automatic fire, bar 55 is inoperative except when the operating slide fails to return to battery. When the bolt and hence the operating slide fails to return to battery, bar 55 blocks hammer 34 thereby preventing premature discharge of the firearm.

A further modification of the fire control mechanism is shown in assembled relation in Figs. 16 and 18. Here again the identical sear release mechanism is utilized for semi and full automatic fire, including the eccentric means for effecting such change. This particular modification utilizes a substantially different hammer latch to restrain hammer 34 from following the bolt forwardly during automatic fire.

Such hammer latch is shown at 63 and comprises a lever-like member, the rear end 64 of which is offset as shown in Fig. 17 so that such end will lie against the right face of hammer 34. The top surface of the rear end portion 64 of latch 63 is rounded as shown at 65. Such surface is rounded to permit a transverse stud 61 on the hammer to ride along such curved surface. The extreme rear end of latch 63 is squared as shown at 66. The forward end of latch 63 is rounded and is pivotally mounted to trigger guard 4 by transverse pin 7. A short distance to the rear of pin 7 a stud 67 is suitably and rigidly secured

5 to latch 63. Latch 63 is raised upwardly by a torsion spring 30 secured to pin 7 to engage stud 61 to hold hammer 34 in the cocked position. A cam bar 69 comprising a forward portion 68 and a rearwardly extending spring-like arm portion 70 is provided to actuate latch 63. On the forward end of cam bar 69 an upstanding lug 71 is provided, the top of which is bent inwardly as shown at 72 to engage the top of operating slide 11. The rear end of lug 71 is likewise bent inwardly to engage the front surface of slide 11, thereby providing means for attaching bar 69 to slide 11. Somewhat to the rear of lug 71 there is provided an inwardly projecting lug 74. Such lug engages a recess 76 normally provided at the rear portion of slide 11, thus securing cam bar 69 against longitudinal movement relative to slide 11.

The extreme rear end of arm 70 is sloped downwardly as shown at 73. Such sloped surface acts as a cam as will be presently described. The sloped end 73 of cam bar 69 is located to the rear of stud 67 on hammer latch 63 so that such sloped end contacts stud 67 only when slide 11 is practically at its extreme forward position.

As previously mentioned, the hammer latch is provided to restrain the hammer from following the bolt forwardly to the closed position until the bolt is locked, thus preventing premature discharge of the cartridge in full automatic fire. Cam bar 69 reciprocates with slide 11. On the recoil stroke of slide 11 and hence bolt 3, hammer 34 is of course rotated to the cocked position. While hammer 34 is rotated to such position, stud 61 passes over the arcuate surface 65 on the rear end 64 of latch 63 and engages squared end 66 of such latch. Assuming trigger 21 is held rearwardly and selector 23 is in its automatic fire position, sear 22 cannot engage sear notch 38 20 of hammer 34, as previously explained, therefore hammer 34 starts to rotate forwardly due to the bias of hammer spring 60. However, stud 61 contacts the end 66 of latch 63 and the hammer is held in the cocked position shown in Fig. 18.

45 Latch 63 is restrained from rotating in a clockwise direction by the underside of the receiver. As slide 11 moves forwardly, locking the bolt, the sloped cam-like surface 73 of arm 70 strikes stud 67 and latch 63 is forced downwardly. This 50 forces the end 66 of the latch to disengage from stud 61 of the hammer. When such disengagement is effected, slide 11 has reached the limit of its forward movement, hence bolt 3 is securely locked, and hammer 34 is then free to effect discharge of the cartridge without danger of premature ignition.

55 From the foregoing description it is readily apparent to one skilled in the art that a simple, effective fire control mechanism to permit full automatic fire or semi-automatic fire is hereby provided. Further, such mechanism can be readily adapted to firearms arranged to fire only semi-automatically or such mechanism can be readily adapted to any new design of firearm requiring selective full or semi-automatic fire control. It is also apparent that a positive hammer latch is provided which insures that the hammer of the firearm is safely blocked at all times until the bolt of such firearm is securely locked in battery position. Thus premature discharge of the firearm in an unsafe position of the bolt is eliminated.

70 I claim:

75 In an automatic firearm having a receiver, a bolt reciprocable therein forwardly to and rear-

wardly from a battery position, a reciprocable operating member for the bolt and a spring biased hammer pivoted in said receiver and movable by the bolt to its cocked position, the improvement comprising, an actuating bar slidably mounted on the receiver adjacent the operating member, a pair of projections on said actuating bar respectively disposed in the path of rearward and forward movement of the operating member whereby said actuating bar is moved rearwardly as the operating member moves to counter-battery position and forwardly as the operating member moves to battery position, a hammer latch pivotally mounted on the receiver adjacent said hammer, a latching projection on said hammer latch engageable with said hammer in its cocked position, said actuating bar having a cam slot therein adjacent said hammer latch, a projecting stud on said hammer latch engageable in said cam slot, said cam slot being constructed and arranged to pivot said hammer latch to engage said

latching projection with said hammer as the operating member moves into counter-battery position and to release said hammer as the operating member moves into battery position.
